UNITED STATES PATENT OFFICE.

EMIL JOSSE, OF BERLIN, GERMANY, ASSIGNOR TO AKTIEBOLAGET VAPORACKUMULATOR, OF STOCKHOLM, SWEDEN, A CORPORATION.

STEAM GENERATION IN TWO STAGES.

Application filed August 2, 1922. Serial No. 579,254.

To all whom it may concern:

Be it known that I, EMIL JOSSE, a subject of Germany, residing at Berlin, Germany, have invented certain new and useful Improvements in Steam Generation in Two Stages, of which the following is a specification.

My invention relates to steam plants and more particularly to plants equipped with steam accumulators in which steam is stored at times when there is a surplus of steam generation over steam consumption and from which steam is delivered into the steam lines of the plant for purposes of low pressure steam consumption at times when the demand for steam exceeds the steam generation.

My invention has for its primary object to generate steam in two stages and in the preferred embodiment this is accomplished by generating high pressure steam for use in the plant in a boiler of ordinary type and generating low pressure steam in a separate container which constitutes an accumulator. A further object of my invention is to obtain a better utilization of the heating surfaces and the flue gases than has hitherto been possible. This is accomplished by the arrangement of a feed heater, preferably heated by flue gases, an accumulator, and a primary boiler in a novel way as hereinafter set out.

Other objects of the invention will be apparent as the description proceeds.

The accompanying drawing shows, more or less diagrammatically, one form of my invention.

Referring to the drawing:

1 designates the primary steam generator which may constitute a boiler of any known type. In this primary steam generator high pressure steam is generated for use in high pressure steam consumers of any kind, the high pressure section H of a turbine being shown by way of illustration. 2 is a flue gas feed water preheater which is so amply dimensioned that the feed water will be preheated to a high temperature, for example, 300° F. at a normal load. Feed water is forced into the preheater 2 by means of the pump 4, and conduits 6 and 7. The water passing into the preheater, as is customary in steam plants, has a temperature of approximately 100° to 120° F. The pump 4 forces the feed water through the conduit

7 and through the tubes of the preheater 2 in countercurrent to the flow of flue gases through the waste heat flue 22. The feed water on leaving the preheater passes through conduit 8. From this conduit the feed water flows into the accumulator 3.

The accumulator 3 is, in effect, an auxiliary steam generator for low pressure steam in which there is a partial generation of steam by means of a drop in pressure. At the lower pressure, the heat of liquid contained in the feed water is less. The difference in heat content of the liquid between the respective pressures is used to cause an evaporation of a part of the feed water. The low pressure steam thus generated in the accumulator by flash is used in the low pressure consumers of the plant. A second boiler feed pump 5 draws water from the accumulator 3 and forces the same through conduit 10 to the primary generator.

If desired a valve 16 may be inserted in conduit 8, the said valve operating to maintain the pressure in the preheater constant preferably at the maximum value of the steam pressure in the accumulator, so that the pressure in the preheater is not subject to variations in the pressure of the accumulator. I have shown, in the drawings for purposes of explanation, one form of valve which will perform the function ascribed to it but it is to be understood that any type of valve which will perform this function may be used. By means of valve 16 the feed water delivered to the accumulator from preheater 2 contains more heat of liquid than if the pressure in the preheater is the same as and varies with the pressure in the accumulator, thus allowing a greater steam generation by flash in the accumulator. Furthermore valve 16 constitutes a protection against boiling and evaporation in the preheater 2, allowing a higher water temperature in the preheater. When the valve 16 is not used, the pressure of the preheater is the same as the pressure in the auxiliary generator and varies therewith.

The accumulator 3 supplies low pressure steam by means of the conduits 13 and 23 to the low pressure consumers of the plant. This steam may be used for heating purposes as indicated at R or for generation of power in the intermediate stages of a steam engine or steam turbine, as indicated at M. It is obvious that the steam drawn off

through conduit 13 may be used in any consumers using steam of relatively low pressure.

In order to heat the contents of the accumulator 3, a second flue gas preheater 17 may be inserted in the waste heat flue 22 before the preheater 2. Water is circulated from the accumulator by means of the circulating pump 18 through the conduit 19, 5 through the preheater 17, through conduit 20 and back to the accumulator. If desired a valve 21, similar in operation to the valve 16 may be inserted in conduit 20, whereby the pressure in preheater 17 is maintained 10 higher than the pressure in the auxiliary generator 3, thus allowing a higher temperature of water in the preheater 17.

To take care of surplus steam generation in the primary generator 1 a conduit 12 connects the steam dome of the primary generator with the water space of the accumulator, and in this conduit is inserted a valve 11, the operation of which is similar to that of the valve 16. This valve 11 is set to open 25 at a somewhat lower pressure than the safety valve 24 on the boiler 1, and when the pressure in the boiler exceeds the pressure at which the valve 11 opens, the excess of steam generated is admitted into the water 30 space of the accumulator whereby the water contained in the accumulator is heated and the pressure therein is raised, so that this heat stored can be withdrawn at some other time in the form of low pressure steam, 35 by drop of pressure.

When the quantity of water delivered by preheater 2 is greater than the demand for feed water in the primary boiler the auxiliary generator 3 constitutes a feed water accumulator; when there is a greater absorption 40 of heat in preheater 2 than there is a demand for low pressure steam, the auxiliary generator 3 constitutes a heat accumulator: when there is a surplus of steam generation 45 in the primary generator, and the excess steam is stored in the auxiliary generator 3, it constitutes a steam accumulator.

In order to avoid heat losses due to radiation the accumulator may be insulated by 50 non-conducting material indicated at 25.

While I have shown and described one form of my invention I wish it understood that the invention is not limited to the precise embodiment set forth but may be modified within the scope of the appended claims.

What I claim as new and desire to secure by Letters Patent of the United States of America is:

1. In a steam plant, means to generate 60 high pressure steam comprising a boiler of ordinary type, a high pressure steam consumer connected to receive steam from said boiler, a preheater to heat water for use in said boiler, means to generate low pressure steam comprising a container interposed be-

tween said preheater and said boiler, in which container a drop in pressure is utilized to flash said low pressure steam and a consumer to receive said low pressure steam.

2. In a steam plant, a primary boiler, a feed preheater to heat water for use in said primary boiler, means to force water through said preheater at a different rate than the rate of demand for feed water by the primary boiler, an accumulator, a conduit conducting water from said preheater to said accumulator, the accumulator serving to store the surplus of feed water passing through the preheater over the boiler demand a conduit conducting water from said accumulator to said primary boiler, a pump in said last mentioned conduit, a consumer, and a conduit conducting steam from said accumulator to said consumer. 70 75 80

3. In a steam plant, a primary boiler generating steam at substantially constant pressure, a high pressure consumer, means to conduct steam from said primary boiler to said high pressure consumer, an accumulator, means to force water from said accumulator to said primary boiler, a preheater, a conduit conducting water from said preheater to said accumulator, a valve in the last-mentioned conduit operating to maintain a higher pressure in said preheater than 90 in said accumulator, a low pressure consumer, and a conduit leading steam from said accumulator to said low pressure consumer thus allowing a drop of pressure between said preheater and said accumulator and in said accumulator to flash steam for low pressure consumption in the plant. 95 100

4. In a steam plant, a primary boiler generating steam at substantially constant pressure, a high pressure consumer, means to conduct steam from said primary boiler to said high pressure consumer, an accumulator adapted to flash steam and to operate under varying pressures, a preheater, a conduit leading water from said preheater to said accumulator, means to force water from said accumulator to said primary boiler, a low pressure consumer, means to lead steam from said accumulator to said low pressure consumer, and means to maintain the pressure in the preheater constant. 105 110 115

5. In a steam plant, a primary boiler generating steam at substantially constant pressure, an accumulator adapted to flash steam and to operate under varying pressures, a preheater, a conduit leading water from said preheater to said accumulator, means to force water from said accumulator to said primary boiler, a consumer, means to lead steam from said accumulator to said consumer, means to maintain the pressure in the preheater constant, a second preheater, conduits connecting said second preheater with said accumulator, and means to maintain circulation in said second preheater. 120 125 130 135

accumulator and conduits connected therebetween.

6. In a steam plant, a primary boiler generating steam at substantially constant pressure, a high pressure steam consumer, means to conduct steam from said primary boiler to said steam consumer, an accumulator adapted to flash steam and to operate under varying pressures, a preheater, means to 10 supply water to said preheater a conduit leading water from said preheater to said accumulator, means to force water from said accumulator to said primary boiler, a low pressure consumer, means to lead steam 15 from said accumulator to said low pressure consumer, means to maintain the pressure in the preheater constant, a steam conduit extending between said primary boiler and the water space of said accumulator, and a 20 valve in said conduit operating to open when the boiler pressure rises above a predetermined value and allow surplus steam generated to pass into the accumulator to be condensed therein.

7. In a steam plant, a primary boiler, a waste heat flue, a preheater in said flue, an accumulator adapted to flash steam upon drop of pressure, a conduit connecting said preheater with said accumulator, means to 25 force water from said accumulator to said primary boiler, a consumer, a conduit leading steam from said accumulator to said consumer, a second preheater in said flue, and means to cause circulation through said 30 accumulator and said second preheater.

8. In a steam plant, a primary boiler, an accumulator, a preheater, a conduit conducting water from said preheater to said accumulator, and a conduit conducting water 40 from said accumulator to said boiler.

9. The method of operating a steam plant which comprises preheating feed water, discharging the preheated water into an accumulator, flashing steam from said water, utilizing the steam thus generated for low 45 pressure consumption in the plant, and pumping the remainder of the water to a primary boiler for the generation of high pressure steam.

10. The method of operating a steam plant which comprises preheating feed water by means of flue gases, discharging the preheated water into an accumulator, flashing steam from said water, utilizing the 55 steam thus generated for low pressure consumption in the plant, and pumping the remainder of the water to a primary boiler for the generation of high pressure steam.

11. The method of operating a steam 60 plant which comprises preheating feed wa-

ter at constant pressure, discharging the preheated water into an accumulator and storing the same therein, flashing steam from said water, utilizing the steam thus generated for low pressure consumption in 65 the plant, and pumping the remainder of the water to a primary boiler for the generation of high pressure steam at a rate different from and independent of the rate of discharge of water into the accumulator. 70

12. The method of operating a steam plant which comprises preheating feed water, discharging the preheated water into an accumulator, flashing steam from said water, utilizing the steam thus generated for 75 low pressure consumption in the plant, pumping water from the accumulator to a boiler for generation of high pressure steam and storing surplus steam generated in the 80 accumulator.

13. The method of generating steam in two stages which comprises conducting water in a path, delivering heat to the water, causing a generation of low pressure steam from part of the water, utilizing the steam 85 for low pressure consumption, raising the pressure of the water which has not been converted into steam and applying heat to this water at higher pressure to generate 90 high pressure steam therefrom.

14. The method of generating steam in two stages which comprises heating a quantity of water, lowering the pressure in the water and causing a partial generation of steam therefrom by drop in pressure, conducting the steam generated to use in low pressure consumers, raising the pressure of the remaining water, applying heat thereto and generating high pressure steam therefrom. 100

15. The method of generating steam in two stages which comprises conducting water through a feed water preheater, applying heat to the preheater, flashing a part of the water into steam, leading the low pressure consumers, raising the pressure of the remaining water, and generating high pressure steam therefrom by the application of heat. 105

16. In a steam plant, a primary boiler, an accumulator, a consumer, a preheater, a conduit conducting water from said preheater to said accumulator, a conduit conducting water from said accumulator to said boiler, a conduit leading steam from said accumulator to said consumer, and additional means to supply heat to the accumulator. 110 115

In testimony whereof I affix my signature.

EMIL JOSSE.

Certificate of Correction.

It is hereby certified that in Letters Patent No. 1,583,557, granted May 4, 1926, upon the application of Emil Josse, of Berlin, Germany, for an improvement in "Steam Generation in Two Stages," an error appears in the printed specification requiring correction as follows: Page 3, line 105, claim 15, before the word "low" insert the words *low pressure steam thus generated to*; and that the said Letters Patent should be read with this correction therein that the same may conform to the record of the case in the Patent Office.

Signed and sealed this 8th day of June, A. D. 1926.

[SEAL.]

M. J. MOORE,
Acting Commissioner of Patents.
